GAMEBOARD

Victor S. Stedman, 6 Blair St., Worcester, Mass.

Filed May 15, 1964, Ser. No. 80,040

Term of patent 3½ years

(Cl. D34—5)

The figure is a plan view in elevation of a gameboard showing my new design. The board is of conventional thickness.

The drawing is lined for color. The reverse side is plain.

I claim:

The ornamental design for a gameboard, as shown and described.
